CLAIM

The ornamental design for a rotorcraft with blades, as shown and described.

DESCRIPTION

FIG. 1 is a top front perspective view of a rotorcraft with blades showing my new design;

FIG. 2 is a top rear perspective view thereof;

FIG. 3 is a bottom rear perspective view thereof;

FIG. 4 is a bottom front perspective view thereof.

FIG. 5 is a front elevational view thereof;

FIG. 6 is a rear elevational view thereof;

FIG. 7 is a left side elevational view thereof;

FIG. 8 is a right side elevational view thereof;

FIG. 9 is a bottom plan view thereof; and,

FIG. 10 is a top plan view thereof.

The broken lines showing the doors and windows in FIG. 1 through 5 and FIG. 7 through 9; the rotors and air inlet in FIGS. 1, 2, and 10; the air outlets in FIG. 2 through 9; the horizontal and vertical stabilizers in FIG. 1 through 10; the tri-wheeled landing gear in FIG. 1 through 9; and the balancing box in FIG. 1 through 9; are all included for the purposes of illustrating portions of the rotorcraft with blades that form no part of the claimed design.
